ANCHOR DAVIT

Walter Uebelhoer, Snyder, N.Y., assignor to Marwal Products Corporation, Buffalo, N.Y.

Application January 30, 1958, Serial No. 712,231

17 Claims. (Cl. 114—210)

This invention relates generally to the anchor handling art, particularly in relation to small and medium sized boats, and more specifically to a new and useful anchor davit for that purpose.

Heretofore, the handling of anchors on small and medium sized boats has been fraught with difficulty, inconvenience and potential danger. It is possible to raise and lower anchors of this size by hand, without the aid of any mechanical means whatever, but such completely manual handling is highly inconvenient, for reasons which are obvious, and places the person handling the anchor under considerable physical strain and in an off-balance and therefore often dangerous position. In addition, there is the problem of raising, lowering and stowing the anchor in a manner insuring that it will not inadvertently strike and injure the boat, and that it will not loosen in a blow and cause damage to the boat or injury to occupants thereof.

While numerous davit constructions have been proposed for this purpose, it is my experience that none of them has solved the problem to the complete satisfaction of boat owners, because they have been either completely impractical, too complex and/or expensive, too apt to become fouled, not consistently dependable, or have presented some other disadvantage.

Accordingly, it is a primary object of my invention to provide a davit construction, particularly adapted for use with boats, which is quickly and easily operated to raise, lower and/or stow an anchor in a manner precluding accidental striking of the anchor against the boat.

Another object of my invention is to provide an anchor davit having the foregoing advantageous characteristics and which is relatively simple and inexpensive in construction, while being extremely durable and dependable in operation.

In one aspect thereof, an anchor davit constructed in accord with my invention is characterized by the provision of a support movable on a base between anchor stowed and anchor lowered positions, a pulley mounted on the support, a rope trained over the pulley and carrying an anchor, means for holding the anchor against lowering movement relative to the support, and means responsive to swinging movement of the anchor toward the support as the anchor is raised thereby to actuate the holding means.

In another aspect thereof, an anchor davit constructed in accord with my invention is characterized by the provision of a base, a support mounted on the base for movement between anchor stowed and anchor lowered positions, a pulley mounted on the support, a rope trained over the pulley and an anchor carried by the rope, the support being adapted to receive the anchor thereagainst for stowing or chocking, together with means automatically holding the anchor against lowering movement relative to the support and thereafter chocking the anchor securely against the support for stowing as the support is moved from anchor lowered to anchor stowed position.

2

In still another aspect thereof, an anchor davit constructed in accord with my invention is characterized by the provision of a support pivoted on a base between anchor stowed and anchor lowered positions, a pulley mounted on the support, the pulley being arranged to have an anchor rope trained thereover, and spring motor means for moving the support out of its anchor chocked position including a housing, a plunger movable relative to the housing and projecting therefrom, spring means carried by the housing and normally biasing the plunger to its fully projected position, the motor being pivoted to the base in spaced relation to the support for movement about a generally parallel pivot axis and being adapted to be engaged by the support as the latter is pivoted toward its anchor stowed position whereby anchor stowing movement of the support telescopes the plunger into the housing to store up energy in the spring.

The foregoing and other objects, advantages and characterizing features of an anchor davit constructed in accord with my invention will become clearly apparent from the ensuing detailed description of a presently preferred embodiment and one modification thereof, together with the accompanying drawings illustrating the same wherein like reference numerals denote like parts throughout the various views and wherein:

Fig. 1 is a top plan view of an anchor davit of my invention in its anchor lowered position, the anchor rope being shown in phantom;

Fig. 2 is a side elevational view thereof, certain parts being broken away for ease of illustration and certain parts being shown in section to more clearly illustrate certain details;

Fig. 3 is a side elevational view thereof in a position intermediate its anchor stowed and anchor lowered positions, being the position at about which the anchor rope clamp is actuated, certain parts being broken away and others being shown in section for greater clarity;

Fig. 4 is a side elevational view thereof in its anchor stowed position, certain parts being broken away and others being shown in section for greater clarity;

Fig. 5 is an enlarged, fragmentary view corresponding generally to that of Fig. 3, with certain parts being shown in section to more clearly illustrate certain details;

Fig. 6 is a view similar to Fig. 5, but with the davit in the anchor lowered position thereof illustrated in Fig. 2;

Fig. 7 is a fragmentary detail view of the anchor guide means;

Fig. 8 is a fragmentary sectional view taken about on line VIII—VIII of Fig. 2;

Fig. 9 is a view corresponding to Fig. 6 but showing a modified arrangement for holding the anchor against lowering movement relative to the support;

Fig. 10 is a sectional view thereof with the anchor alining parts engaged, being taken about on line X—X of Fig. 11;

Fig. 11 is a top plan view thereof;

Fig. 12 is a side elevational view thereof with the anchor holding means engaged; and

Fig. 13 is an end elevational view thereof, with the parts about in the position shown in Fig. 10.

The illustrated embodiment of an anchor davit constructed in accord with my invention comprises a base, generally designated 1, adapted to be secured to the deck 2 of a boat as by means of bolts 3 or the like extending through ears 4. In addition to mounting the movable davit mechanism about to be described, base 1 also can function as a support for a housing for running lights, and the like, as indicated at 1' (Fig. 2) as will be readily apparent to those skilled in the art.

It is contemplated that base 1 will be secured to boat deck 2 at a central position in the bow, thereby enabling

a support, generally designated 5, to project forwardly of the boat, ahead of the bow, when in its anchor lowered position illustrated in Figs. 1 and 2. Support 5 comprises a pair of struts 6, preferably of tubular construction, each pivotally mounted adjacent its lower or inner end on base 1 as by means of a bolt 7 passing through an ear 7'. Each strut 6 carries at its upper or outer end a plate 8 forming part of a pulley supporting bracket, which plates 8 are welded or otherwise secured to support struts 6 and mount a pulley 8' over which the anchor rope 9 is trained. Pulley 8' is journaled on bracket plates 8, as by a bolt 11, and is grooved in the usual manner to receive the rope 9.

There is shown an anchor, generally designated 12 (Figs. 3 and 4), of a known construction which is no part of my invention, although I believe that an anchor of the illustrated construction is particularly well suited to use with the davit of my invention. Such an anchor comprises a shank 13 slotted from one end to substantially the other end thereof, as illustrated at 14, to enable sliding movement therealong of a ring 15 to which the anchor rope is connected. At its other end the anchor shank 13 is tapered and enlarged, to provide a body portion 15' on which a pair of flukes 16 are supported for pivoting movement relative thereto limited by opposed shoulders 17 on body 15. This construction presents a very considerable advantage in that if the anchor is caught in one position, with the flukes 16 locked under a projecting rock shelf, or the like, the anchor can be disengaged by simply moving the boat to the other side of the anchor, causing ring 15 to slide along shank 13 toward the enlarged end 15', and then pulling the anchor out backwards to free it from whatever obstruction it has encountered. Of course, the davit of my invention is readily adapted for use with other anchor constructions.

The anchor 12 is adapted to be raised, and the anchor and its davit are adapted to be moved to the stowed position illustrated in Fig. 4, by pulling upon the anchor rope 9, as will be described in greater detail hereafter.

For swinging support 5 and anchor 12 from the anchor stowed position of Fig. 4 to the anchor lowered position of Fig. 2, I provide means in the form of a spring motor, generally designated 19, comprising a housing 20 carried by a clevis bracket 21 pivotally mounted on base 1 as by a bolt 22 and containing a compression type spring 23. A plunger, comprising a rod 24 projecting from housing 20 is provided at its outer end with a generally U-shaped bracket 26 mounting a pulley 27. The upper end of housing 20 is closed, as by a plug 28 held in place by a screw 29 through the wall of housing 20, and plunger rod 24 normally is urged by spring 23 to its fully projected position with washer 25 bearing against end plug 28.

Spring motor 19 and support 5 are provided with cooperating shoulders, for cocking the motor upon movement of the support to anchor stowed position, and whereby release of the support will initiate movement thereof by the spring motor toward anchor lowered position. To this end, bracket 26 of plunger 24 can project outwardly beyond pulley 27, to provide at its outer end shoulders 30 adapted to engage beneath and bear against a cooperating shoulder in the form of an angle 31 carried by the support struts 6 and spanning the same intermediate the opposite ends thereof. Thus, upon rearward movement of support 5 from the position of Fig. 3 toward that illustrated in Fig. 4, the outer end 30 of the motor plunger 24 will engage beneath the generally horizontal leg of support bracket 31, whereby continued rearward movement of support 5 will telescope plunger 24 into motor housing 20, compressing motor spring 23 and thereby storing up potential energy in the same. As clearly illustrated in Fig. 4, when the davit is in its anchor stowed position the motor plunger is substantially fully retracted, and the motor thereby is

taut or cocked, so that upon releasing rope 9 to permit anchor lowering movement of the davit the compressed spring 23 forces plunger 24 outwardly of motor housing 20, the plunger shoulders 30 bearing against bracket 31 to swing support 5 up and over, past its dead center point, following which the weight of anchor 12 will continue the forward, anchor lowering movement of the davit.

It will be appreciated that spring 23 is of substantial strength, more than sufficient to lift support 5 and the anchor 12 carried thereby from the nearly horizontal, stowed position illustrated in Fig. 4 to a nearly straight vertical position, just before that illustrated in Fig. 3, beyond which the weight of support 5 and anchor 12 combine to continue the desired forward movement thereof. While spring 23 is selected to have sufficient strength to accomplish this, it will be seen that motor 19 reaches its vertical, dead center position prior to the time when support 5 reaches a corresponding position, because their pivot points are spaced apart fore and aft of the boat to which they are attached. To insure movement of support 5 past its dead center position, a torsion spring 32 (Figs. 1 and 4) is provided to swing motor 19 past dead center and to the position illustrated in Fig. 3.

Torsion spring 32 can be mounted in base 1, which comprises a hollow housing for this purpose, being positioned around motor pivot pin 22 and having one end bearing for example on the underside of the top wall of base 1, with its other end locked to motor support bracket 21, as through pivot pin 22. Consequently, as motor 19 is cocked upon anchor stowing movement of support 5 torsion spring 32 also is stressed to store up potential energy therein. Such energy is released upon release of rope 9 to swing motor 19 about its pivot 22 past its dead center position and to the position illustrated in Fig. 3, at which point the motor support 21 strikes abutments or stops 33 on base 1, to limit further forward movement thereof.

Thus, spring motor 19 is energized automatically upon moving the anchor to its stowed position illustrated in Fig. 4, and is at all times ready, without more, to swing the anchor and its support 5 out of stowed position to lower the anchor. In addition, it is a particular feature of my invention that when support 5 is in anchor lowered position (Fig. 2), the spring motor pulley 27 receives anchor rope 9 and the spring motor provides a lever arm facilitating lifting of support 5 by simply pulling on the anchor rope.

This is because spring motor 19 is held by stops 33 in a generally upright position, just a few degrees past dead center or straight vertical, whereby spring motor 19 holds anchor rope 9 well off the deck in a substantially elevated condition relative to support pulley 8'. It would be quite difficult to lift support 5 from the position thereof in Fig. 2 by pulling rope 9 if the latter simply lay on deck 2, because there would be no lifting moment. However, with the instant invention the spring motor provides a very effective lever arm which is fully operative when support 5 is in a generally horizontal position, making it relatively easy to move support 5 out of such position.

This arrangement also offers a significant advantage with respect to load distribution, because when the anchor is suspended in the position of Fig. 2, as much as sixty (60) percent of the load is on spring motor 19, and most of this part of the load is transferred by motor 19 directly to housing 20 and deck 2 in compression. This greatly reduces the effect of the load suspended on the outer end of support 5, and thereby avoids tearing of the davit off deck 2 such as might otherwise tend to occur.

In addition to this novel anchor davit motor it is a particular feature of my invention that, upon predetermined anchor stowing movement of the davit, as when it reaches approximately the position illustrated in Fig.

3, the anchor is automatically held against lowering movement relative to the davit support 5, so that there is no danger of the anchor suddenly dropping at this point and damaging the boat deck, and upon further anchor stowing movement thereof the anchor is automatically clamped to the support 5 against movement relative thereto. In addition, means are provided to prevent swinging of the anchor as the davit is raised from its lowered position to the clamping position illustrated in Fig. 3.

In the embodiment of Figs. 1-8, this is accomplished by clamping the anchor rope, and to this end, the offset brackets 8 mounted on support struts 6 also carry a clamping mechanism including a member 35 which has a serrated under-surface 36 facing the pulley groove and is carried by side plates 37 pivoted to brackets 8 in offset relation to pulley 8', as at 38. A clamp actuating member 39 also is mounted on bracket 8, comprising for example spaced side plates 41 pivoted adjacent one end on bracket 8, as at 42, and bridged by a plate 43. The anchor rope 9 is trained over pulley 8', between it and clamp part 35, and passes between the actuating member side plates 41 and through an eyelet 44, having a beveled entrance 45, carried by an end plate 46 of generally inverted V-shape in cross section. In this way, rope 9 is constrained to move through eyelet 44, for a purpose to be described. A cooperating plug member 47 has a bore therethrough terminating in a recess to receive the end of rope 9, as indicated at 48 in Fig. 5, and also pivotally mounts the anchor ring 15. At its upper end, plug 47 is formed with a tapered surface having outwardly converging sides 49 which complement and are adapted to nest with the side walls of end plate 46 for being held against swiveling relative thereto.

The V-shaped parts 46 and 47 have their apexes alined in a direction at right angles to the plane of the flukes 16, whereby as the anchor 12 is raised out of the water, by pulling on rope 9, the plug 47 engages the clamp actuating member end plate 46 and is automatically positioned thereby for nesting therewith. The nesting parts 46 and 47 hold the anchor against undue swiveling movements, such as might otherwise cause it to strike and damage the boat, as it is lifted by the davit up into stowed position on the boat. If part 47 is not alined with part 46 at the position illustrated in Fig. 7, it will automatically be cammed thereby into proper alinement. Anchor stowing movement of support 5, caused by continued pulling on anchor rope 9, lifts the anchor 12 with the anchor and clamp actuator 39 moving substantially as a unit so that, as support 5 is moved toward the position illustrated in Fig. 3, the weight of anchor 12 swings it and actuating member 39 inwardly toward support 5 about the pivot axis 42 of member 39.

The inner end 50 of clamp 35 is formed to clear the inner end 51 of actuating member 39 whenever support 5 is between the positions thereof illustrated in Figs. 2 and 3. However, as support 5 moves to the position thereof shown in Fig. 3, the weight of anchor 12 swings it and actuating member 39 about pivot 42 causing a shoulder 52 on actuating member 39 to engage beneath a shoulder 53 on clamp 35, whereby continued pivoting of member 39 about its axis 42 will forcibly pivot clamp 35 about its axis 38, in a counterclockwise direction as viewed in Fig. 5, to force the clamp part 35 firmly against rope 9 and clamp it against pulley 8'. Therefore, at the position shown in Figs. 3 and 5, anchor 12 not only is held against undue swiveling, but in addition the anchor rope 9 and pulley 8' are clamped against anchor lowering movement. As a result, the anchor 12 cannot accidentally drop and strike deck 2 whenever the davit is between the positions of Figs. 3 and 4, this being accomplished automatically without any attention on the part of the operator, being solely in response to swinging movement of anchor 12 toward support 5 as they are moved toward anchor stowing position.

Support 5 is provided with anchor receiving means in the form of a bed comprising a plate 55 welded, bolted or otherwise secured to support struts 6, as indicated at 56, and having outwardly diverging wings 57 at opposite sides thereof, the plate 55 being adapted to receive the anchor flukes 16 thereagainst when the anchor is in its stowed position. Thus, as support 5 swings rearwardly from the position illustrated in Fig. 3 to that illustrated in Fig. 4 the anchor, which is held by nesting parts 46 and 47 and by clamp 35 with its flukes 16 aligned to lie generally flatwise against the plate 55, moves into that position as clearly illustrated in Fig. 4. To securely clamp the anchor against the support 5, so that it is immovable relative to the davit when in its stowed position and cannot accidentally be dislodged therefrom and strike deck 2, I provide means in the form of clamping arms 58 of generally right angular form having one leg pivoted to the support struts 6, as at 59, and adapted to swing upwardly under and over the anchor flukes 16 to clamp them against plate 55 and thereby securely lock anchor 12 in stowed position as clearly illustrated in Fig. 4. Normally, clamp arms 58 hang free and clear of anchor 12, to permit it to move against the plate 55 as the davit moves into stowed position, and I provide means automatically operable to cause arms 58 to thereafter clamp anchor 12 in stowed position, such means comprising for example a bail-like actuator member 61 pivotally connected adjacent its opposite ends to arms 58 outwardly of their pivots 59. Actuator 61 is aligned with a shoulder or dog 62 carried by the motor housing 20, so that after support 5 moves rearwardly from the position of Fig. 3 toward that of Fig. 4 and engages plunger 24, the bail 61 is caught on dog 62. Dog 62 prevents inward movement of actuator 61 along motor housing 20, whereby continued rearward movement of support 5 causes upward pivoting movement of arms 58 around and over the anchor flukes 16 to securely clamp them against plate 55 when the anchor is in its stowed position illustrated in Fig. 4.

Thus, it is seen that with an anchor davit constructed in accord with my invention, as the anchor is raised it is immediately and automatically held against undue swiveling out of proper alinement for movement into stowed position, from the time the davit begins to raise the anchor, and the anchor rope is clamped against lowering movement automatically when the davit reaches a position such that if the anchor were to fall it would damage the boat. Continued movement of the davit to stowed position energizes the spring motor 19 for subsequently throwing out or lowering the anchor upon releasing the anchor rope, and automatically causes the anchor to be firmly clamped to the davit for being securely held in stowed position on deck. This is provided in a very compact structure susceptible of a highly pleasing and ornamental appearance, operable with minimum effort and maximum dependability.

Anchor raising and stowing movement is accomplished by pulling on rope 9, which can be done manually or by an appropriate hoist, not illustrated, and anchor lowering movement is accomplished automatically, by simply paying out rope 9.

To provide clearance for end 15' of anchor 12, or as might otherwise be necessitated by a particular anchor, plate 55 can be cut away, as indicated at 64, and cushioning means 65 can be provided on motor housing 20 and/or wherever necessary to prevent marring of the davit by the anchor. Also, to help support the support 5 when in its lowered position and maintain the same free and clear of deck 2, generally U-shaped brackets 66 are provided on base 1 on opposite sides thereof ahead of the pivot 7, to receive struts 6.

Where more power is required for lifting action, multiple motors 19 can be utilized.

A modified anchor holding arrangement is illustrated in Figs. 9-12, wherein the davit pulley 8' is mounted on

struts 6' which correspond to struts 6 except that, instead of providing a pulley supporting bracket in the form of separate plates affixed to the struts, the outer ends of struts 6' are flattened, as indicated at 6", and apertured to receive therethrough a bolt 11' carrying a bearing sleeve 70 on which the pulley 8' is journaled. Bearing sleeve 70 also serves to maintain the outer ends 6" of struts 6' in properly spaced relation, and lock nuts 11" or the like secure the parts in assembled relation.

Bearing sleeve 70 also serves as a journal for the clevis end 71 of a guide member 72 having adjacent its other end an enlarged head 73 on the underside of which there is formed a plug receiving seat 74 of generally inverted V-shape.

Anchor rope 9 trains over the grooved pulley 8', and carries at its end an anchor plug, generally designated 75. Plug 75 comprises a tubular body part 76 having an upper surface 77 of generally inverted V-shape, complementing and interfitting with seat 74 on guide member 72. A shouldered nipple 78 is carried by body 76 and projects through the guide surfaces 77 thereof for passing through an opening 79 in the plug receiving seat 74 and into the hollow head 73 of guide member 72. At its outer end, nipple 78 has a shouldered locking part in the form of an annular groove 81 of generally V-shaped cross sectional form.

Plug 75 is conveniently secured to anchor rope 9 by means including an internal sleeve 82 having a tapered aperture 83 receiving the end of the rope, and cooperating with a tapered internal plug 84 which is inserted into the end of the rope to splay the same and clamp it against the tapered aperture 83, as clearly illustrated in Fig. 10. The parts 82 and 84 preferably are molded of nylon, and serve to securely lock plug 75 to anchor rope 9, the locking action being completed by means including an external plug 86 having a split, tubular shank 87 of generally U-shaped cross-sectional form which has threaded engagement with sleeve 76, for ramming home the internal plug 84. The plug 86 is split to receive therethrough ring 15 attached to shank 13 of anchor 12, and can be locked in place by means including for example a set screw 88 in member 76 adapted to extend between the split sections of shank 87 to prevent rotation of plug 86. In this way, the anchor attached plug 86 can be locked in the position which will maintain the anchor in proper positional alignment with support plate 55 for lying thereagainst, when the cooperating guide surfaces 74 and 77 are properly engaged as illustrated in Figs. 10-13.

A second shouldered locking part 90, having an end 91 of generally V-shaped cross sectional configuration to interfit with groove 81 in nipple 78, is carried by a generally U-shaped bracket 92 which is adjustably locked against movement relative to the davit support, the bracket 92 engaging on bolt 11' and being locked against movement by nuts 11". Locking pin 90 is in positional alignment with locking nipple 78 when plug 75 is properly seated in guide member 72, but does not engage the locking groove 81 on nipple 78 until the latter is swung through a predetermined angle toward davit support struts 6'.

In use, when the davit is in anchor lowered condition, the parts are in the position illustrated in Fig. 9. However, when the anchor is raised, plug 75 engages the davit guide member 72 and the guide surfaces 74 and 77 cause the plug to seat in a predetermined manner to maintain a predetermined positional alignment of the attached anchor 12 relative to the davit support plate 55, so that the anchor will be received thereagainst in the manner previously described. Further, to insure proper seating of plug 75 against guide member 72, I provide means for elastically resisting movement of guide member 72, which means can take the form of a spring 93 having a coiled portion 94 held in fixed position on bolt 11' and an arm portion 95 which extends across and partially around guide member 72, over the head 73 thereof. In

5 this way spring 93, through its arm 95, resiliently resists upward movement of guide member head 73, causing plug 75 to properly seat therein even if plug surface 77 is initially completely out of alignment with the guide member seat 74.

10 It will be noted that when plug 75 is properly seated, locking nipple 78 projects through the guide member seat into the hollow interior thereof, in alignment with locking pin 90. Then, continued pulling on anchor rope 9 causes the davit to swing rearwardly in the manner previously described, with the struts 6' moving in the direction of arrow 96 (Fig. 12). During such anchor raising movement of the davit the weight of anchor 12 and attached parts causes them to swing inwardly relative to support struts 6' about the pivot axis defined by shaft 11', in the manner previously described with reference to Figs. 1-8, until locking pin 90 engages locking nipple 78. Once these locking parts are engaged, which occurs at about the position shown in Fig. 12, anchor plug 75 is locked 15 against guide member seat 74, and stays locked thereagainst when the davit is between this position and its anchor stowed position. When locked against seat 74, it is impossible for the anchor to drop downwardly relative to the support. The locking arrangement is engaged 20 automatically by movement of the anchor toward the support, and are held engaged by the weight of the anchor, as in the embodiment of Figs. 1-7, but all of this being accomplished in the instant embodiment without touching rope 9 and therefore without injuring the 25 same. It is believed that this is the preferred method of holding the anchor, because it avoids clamping against the rope which clamping produces wear thereon.

30 Where it is desired to vary the point at which locking parts 90 and 78 engage, the position of locking part 90 relative to support struts 6' is readily adjusted by momentarily loosening nuts 11".

35 Also, the arrangement illustrated in Figs. 9-13 has the further advantage that the rope is subject to less wear and tear in its operation through guide member 72. This 40 is because the latter is maintained in its proper position by its own weight and by spring arm 95, and the anchor rope is confined for a considerable portion of its outer end in the nipple 78, whereby there is little or no abrasion of the anchor rope.

45 Of course, the inner ends of struts 6' can be flattened, similar to outer ends 6", for attachment to the base 1. Otherwise, except where noted above the davit of Figs. 9-13 is the same as that illustrated in Figs. 1-8.

50 Accordingly, it is seen that an anchor davit constructed in accord with my invention fully accomplishes the intended objects. While only a presently preferred embodiment and one modification have been disclosed and described in detail herein, it is to be understood that I do not thereby intend that my invention be limited to such details. Instead, I realize that other modifications 55 and variations will readily occur to those skilled in the art, all without departing from the spirit of my invention and the scope of the appended claims.

Having fully disclosed and completely described my 60 invention, together with its mode of operation, what I claim as new is:

65 1. An anchor davit comprising, a base, a support mounted adjacent one end thereof on said base for swinging movement between anchor stowed and anchor lowered positions, a pulley carried by said support adjacent the other end thereof, a rope trained over said pulley, an anchor carried by said rope, said support being provided intermediate its opposite ends with anchor receiving means, first clamp means carried by said support for movement into a position clamping said rope against anchor lowering movement relative to said support upon predetermined movement of said support from its anchor lowered position to its anchor stowed position, and second clamp means carried by said support for movement 70 into a position clamping said anchor in stowed position

against said anchor receiving means upon further predetermined movement of said support from its anchor lowered position to its anchor stowed position.

2. An anchor davit comprising, a base, an elongated support pivoted adjacent one end thereof on said base for anchor raising and lowering movement, a pulley mounted on said support adjacent the other end thereof, a rope trained over said pulley, an anchor carried by said rope, said support having anchor receiving means intermediate its ends, first clamp means mounted on said support adjacent said pulley and operable upon predetermined anchor raising movement of said support to clamp said rope against said pulley, and second clamp means mounted on said support adjacent said anchor receiving means and operable upon further predetermined anchor raising movement of said support to clamp said anchor against said anchor receiving means.

3. An anchor davit comprising, a base, an elongated support mounted adjacent one end thereof on said base for swinging movement between anchor stowed and anchor lowered positions, a pulley mounted on said support adjacent the other end thereof, a rope trained over said pulley, an anchor carried by said rope, said anchor comprising a shank and a pair of flukes carried thereby, plate means mounted on said support intermediate its ends for receiving said anchor flukes generally flatwise thereagainst as said support is moved into its anchor stowed position, clamp arm means mounted on said support adjacent said plate means for movement into a position clamping said anchor flukes thereagainst to secure said anchor in stowed position on said support, guide means operable automatically upon raising said anchor to align said flukes for movement generally flatwise against said plate means, and clamp arm actuator means operable automatically to move said clamp arm means into clamping engagement with said anchor flukes upon predetermined anchor stowing movement of said support.

4. An anchor davit comprising, a base, an elongated support pivoted adjacent one end thereof on said base for anchor stowing and lowering movement, a pulley mounted on said support adjacent the other end thereof for receiving an anchor rope thereover, and motor means for moving said support out of its anchor stowed position to lower an anchor, said motor means comprising a housing, a plunger reciprocable relative to said housing and projecting therefrom, means pivotally mounting said motor means on said base in spaced relation to said support for movement about an axis generally parallel to the pivot axis of said support, spring means mounted in said housing and normally biasing said plunger to its fully projected position, and means carried by said support in line with said motor means for engaging the same and retracting said plunger relative to said housing against the bias of said spring means upon anchor stowing movement of said support, whereby energy is stored up in said spring means for producing anchor lowering movement of said support.

5. An anchor davit comprising, a base, a support mounted adjacent one end thereof on said base for movement between an anchor stowed position and an anchor lowered position, a pulley mounted on said support adjacent the other end thereof for receiving an anchor rope thereover, a housing part mounted on said base in spaced relation to said support for movement about an axis generally parallel to the axis of movement of said support, a plunger part movable relative to said housing part and having an outer end portion extending therefrom, spring means carried by said housing part and normally biasing said plunger part end portion to fully extended position, and means on said support in alignment with said plunger part outer end portion for bearing thereagainst and forcing said plunger into said housing to stress said spring means upon moving said support to its anchor stowed position.

6. An anchor davit as set forth in claim 5, together with a pulley mounted on said plunger part outer end portion for engaging the anchor rope when said support is in its anchor lowered position to provide a lever arm assisting in initially moving said support to raise an attached anchor by pulling on the anchor rope.

7. An anchor davit as set forth in claim 5, together with torsion spring means operatively connected to said housing part adjacent said base for urging said housing about its axis in an anchor lowering direction, said torsion spring means also being stressed upon anchor stowing movement of said support.

8. An anchor davit comprising, base means, an elongated support mounted adjacent one end thereof on said base means for swinging movement between an anchor stowed position and a normally generally horizontal anchor lowered position, pulley means carried by said support adjacent the other end thereof for receiving an anchor rope thereover, and spring motor means for swinging said support out of said anchor stowed position to lower an attached anchor including relatively reciprocable parts, one of said motor parts being mounted on said base means aft of said support means for swinging movement of said motor parts about an axis generally parallel to that about which said support swings, spring means operable between said parts and normally urging the other thereof toward an extended position, pulley means carried by said other part for receiving the anchor rope when said support is in anchor lowered position, stop means limiting swinging movement of said motor parts toward said support to a normally generally upright position slightly beyond the perpendicular, whereby when said support means is in said anchor lowered position said motor parts provide a lever arm holding the anchor rope in an elevated position relative to said support pulley to facilitate lifting said support from said anchor lowered position, and means carried by said support and engaging said other motor part to collapse the same relative to said one motor part and thereby store up potential energy in said spring means and to swing said motor parts rearwardly as said support is moved toward said anchor stowed position.

9. An anchor davit comprising, base means, an elongated support mounted adjacent one end thereof on said base means for swinging movement between an anchor stowed position and a normally generally horizontal anchor lowered position, pulley means carried by said support adjacent the other end thereof for receiving an anchor rope thereover, and spring motor means for swinging said support out of said anchor stowed position to lower an attached anchor including relatively reciprocable parts, one of said motor parts being mounted on said base means aft of said support means for swinging movement of said motor parts about an axis generally parallel to that about which said support swings, spring means operable between said parts and normally urging the other thereof toward an extended position, pulley means carried by said other part for receiving the anchor rope when said support is in anchor lowered position, stop means limiting swinging movement of said motor parts toward said support to a normally generally upright position slightly beyond the perpendicular, whereby when said support means is in said anchor lowered position said motor parts provide a lever arm holding the anchor rope in an elevated position relative to said support pulley to facilitate lifting said support from said anchor lowered position, and means carried by said support and engaging said other motor part to collapse the same relative to said one motor part and thereby store up potential energy in said spring means and to swing said motor parts rearwardly as said support is moved toward said anchor stowed position, together with additional spring means normally urging said motor parts about their swinging axis toward said support to ensure movement of said motor parts to said normally generally upright position,

said additional spring means being stressed automatically to store up potential energy therein upon rearward swinging movement of said motor parts by said support.

10. An anchor davit as set forth in claim 8, wherein said support is provided with means adapted to receive an anchor thereagainst, together with clamp means for clamping an anchor against said anchor receiving means when said support is in said anchor stowed position, said clamp means including arm means mounted on said support to swing into and out of anchor engaging position relative thereto, said clamp arm means swinging out of anchor engaging position when said support is in a generally upright position, and inter-engageable actuating members connected one to said one motor part and the other to said clamp arm means, said other actuating member engaging said one actuating member as said support and said motor parts swing rearwardly to swing said clamp arm means into anchor clamping position as said support moves into stowed position.

11. An anchor davit comprising, base means, an elongated support mounted adjacent one end thereof on said base means for swinging movement between an anchor stowed position and a normally generally horizontal anchor lowered position, pulley means carried by said support adjacent the other end thereof for receiving an anchor rope thereover, and spring motor means for swinging said support out of said anchor stowed position to lower an attached anchor including relatively reciprocable parts, one of said motor parts being mounted on said base means aft of said support means for swinging movement of said motor parts about an axis generally parallel to that about which said support swings, spring means operable between said parts and normally urging the other thereof toward an extended position, pulley means carried by said other part for receiving the anchor rope when said support is in anchor lowered position, stop means limiting swinging movement of said motor parts toward said support to a normally generally upright position slightly beyond the perpendicular, whereby when said support means is in said anchor lowered position said motor parts provide a lever arm holding the anchor rope in an elevated position relative to said support pulley to facilitate lifting said support from said anchor lowered position, and means carried by said support and engaging said other motor part to collapse the same relative to said one motor part and thereby store up potential energy in said spring means and to swing said motor parts rearwardly as said support is moved toward said anchor stowed position, together with additional spring means normally urging said motor parts about their swinging axis toward said support to ensure movement of said motor parts to said normally generally upright position, said additional spring means being stressed automatically to store up potential energy therein upon rearward swinging movement of said motor parts by said support, wherein said support is adapted to receive an anchor thereagainst, together with clamp means for clamping an anchor against said support when the latter is in said anchor stowed position, said clamp means including arm means mounted on said support to swing into and out of anchor engaging position relative thereto, said clamp arm means swinging out of anchor engaging position when said support is in a generally upright position, and inter-engageable actuating members connected one to said one motor part and the other to said clamp arm means, said other actuating member engaging said one actuating member as said support and said motor parts swing rearwardly and being held thereby against movement relative to said one motor part thereby to swing said clamp arm means into anchor clamping position as said support moves into stowed position.

12. An anchor davit comprising, a base, a support mounted on said base for swinging movement between anchor stowed and anchor lowered positions, a pulley mounted on said support, a rope trained over said pulley,

an anchor carried by said rope, and anchor holding means including a first member pivotally connected to said support for movement about the axis of said pulley, said first member having a seat through which said rope passes, a plug carried by said rope between said first member and said anchor, said plug being adapted to engage said seat upon raising said anchor by pulling said rope, a locking part on said plug, and a locking member carried by said support, said locking member being spaced from said locking part when said support is in its anchor lowered position and aligned with said locking part to engage the same and thereby lock said plug against said seat upon predetermined movement of said first member and seated plug toward said support in response to swinging of said anchor toward said support during anchor raising movement thereof, whereby said plug is locked to said seat automatically upon predetermined anchor raising movement of said support.

13. An anchor davit as set forth in claim 12, wherein said seat and said plug have guide means cooperating when engaged to automatically align said anchor in a predetermined position relative to said support.

14. An anchor davit as set forth in claim 13, together with means resiliently forcing said first member guide means into cooperating engagement with said plug guide means.

15. An anchor davit comprising, a base, a support mounted on said base for movement between anchor raised and anchor lowered positions, a pulley carried by said support, a rope trained over said pulley, an anchor carried by said rope, and anchor holding means including a plug carried by said rope between said pulley and said anchor, a member having a plug receiving seat portion interposed between said pulley and said plug pivotally carried by said support for swinging movement of said plug receiving seat portion toward and away from said support, said plug being adapted to seat against said seat portion for swinging movement therewith, and means automatically operable upon predetermined swinging movement of said seat portion and seated plug toward said support to lock said plug against said seat portion, whereby said anchor is automatically held against lowering movement relative to said support upon predetermined anchor raising movement of the latter.

16. An anchor davit comprising, a base adapted to be secured to the deck of a boat, a support mounted adjacent one end thereof on said base for swinging movement between anchor stowed and anchor lowered positions, a pulley carried by said support adjacent the other end thereof, a rope trained over said pulley, an anchor carried by said rope, said support being swung from said anchor lowered position to said anchor stowed position by pulling upon said rope and being provided intermediate its opposite ends with anchor receiving means, first means carried by said support and operable automatically upon predetermined movement of said support from said anchor lowered position toward said anchor stowed position to hold said anchor against lowering movement relative to said support and thereby preclude inadvertent dropping of said anchor onto an associated boat deck, and second means carried by said support and subsequently operable automatically upon further predetermined movement of said support from said anchor lowered position toward said anchor stowed position to clamp said anchor in stowed position against said anchor receiving means.

17. An anchor davit comprising, a base adapted to be secured to the deck of a boat, an elongated support mounted adjacent one end thereof on said base for swinging movement between anchor stowed and anchor lowered positions, a pulley mounted on said support adjacent the other end thereof, a rope trained over said pulley, an anchor carried by said rope, said anchor comprising a shank and a pair of flukes carried thereby, said support being swung from said anchor lowered position to said

anchor stowed position by pulling upon said rope, plate means mounted on said support intermediate its ends for receiving said anchor flukes generally flatwise thereagainst as said support is moved into said anchor stowed position, guide means carried by said support and by said rope and operable automatically upon pulling said rope and raising said anchor at the beginning of movement of said support out of said anchor lowered position to aline said flukes for movement generally flatwise against said plate means, and clamp means mounted on said support in operative 10 association with said plate means and subsequently operable automatically to clamp said anchor flukes in stowed

position against said plate means upon movement of said support into said anchor stowed position.
